(57) **CLAIM**

The ornamental design for an exercising apparatus equipped with weight scale, as shown and described.

DESCRIPTION

FIG. 1 is a perspective view of an exercising apparatus equipped with weight scale showing the new design; FIG. 2 is a front elevation view thereof; FIG. 3 is a rear elevation view thereof; FIG. 4 is a left-side elevation view thereof; FIG. 5 is a right-side elevation view thereof; FIG. 6 is a top plan view thereof; FIG. 7 is a bottom plan view thereof; and, FIG. 8 is a perspective view showing a state of the scale folded.

(Continued)

The broken lines in the drawing figures are for the purpose of illustrating both portions of the exercising apparatus equipped with weight scale and an environment of use and form no part of the claimed design.

1 Claim, 8 Drawing Sheets
